UNITED STATES PATENT OFFICE

110,893

DESIGN FOR A COMBINATION BED AND DESK

William Lipscomb Davis, Nashville, Tenn., assignor to Davis Cabinet Company, Nashville, Tenn., a corporation of Tennessee

Application June 28, 1938, Serial No. 78,125

Term of patent 14 years

To all whom it may concern:

Be it known that I, William Lipscomb Davis, a citizen of the United States of America, residing at Nashville, county of Davidson, State of Tennessee, have invented a new, original, and ornamental Design for a Combination Bed and Desk, of which the following is a specification, reference being had to the accompanying drawing, forming a part thereof.

The figure is a perspective view of the combination bed and desk, showing my new design.

I claim:—

The ornamental design for a combination bed and desk, substantially as shown.

WILLIAM LIPSCOMB DAVIS.
